CLAIM

The ornamental design for a telephone, as shown and described.

DESCRIPTION

FIG. 1 is a perspective view of a telephone with the handset in the base;

FIG. 2 is a perspective view of the telephone with the handset removed from the base;

FIG. 3 is a top elevation view of the base;

FIG. 4 is a bottom elevation view of the base;

FIG. 5 is a right side elevation view of the base;

FIG. 6 is a left side elevation view of the base;

FIG. 7 is a back elevation view of the base; and,

FIG. 8 is a front elevation view of the base.

The broken line showings throughout the views are for illustrative purposes only and form no part of the claimed design.
